[57] CLAIM

The ornamental design for the cooler for golf carts, as shown and described.

DESCRIPTION

FIG. 1 is a perspective view of a first variant of the design attached to a golf cart;

FIG. 2 is a bottom plan view of a first variant of the design attached to a golf cart;

FIG. 3 is a right side elevation view of a first variant of the design attached to a golf cart;

FIG. 4 is a top plan view of a first variant of the design attached to a golf cart;

FIG. 5 is a left side elevation view of a first variant of the design attached to a golf cart;

FIG. 6 is a back end view of a first variant of the design;

FIG. 7 is a front end view of a first variant of the design;

FIG. 8 is a perspective view of a second variant of the design with middle cabinet door in a closed position, attached to a golf cart;

FIG. 9 is a perspective view of a second variant of the design with middle cabinet door in an open position, attached to a golf cart;

FIG. 10 is a bottom plan view of a second variant of the design attached to a golf cart;

FIG. 11 is a right side elevation view of a second variant of the design attached to a golf cart;

FIG. 12 is top plan view of a second variant of the design attached to a golf cart;

FIG. 13 is left side elevation view of a second variant of the design attached to a golf cart;

FIG. 14 is a back end view of a second variant of the design with door in a closed position; and,

FIG. 15 is a front end view of a second variant of the design. The golf cart depicted by means of stippled lines in FIGS. 1 through 5 and 8 through 13 is shown for illustrative purposes only and forms no part of the claimed design.
